UNITED STATES PATENT OFFICE

163,093

SKIRT OR SIMILAR ARTICLE

Davis Cohen, Brooklyn, N. Y.

Application January 10, 1951, Serial No. 13,733

Term of patent 7 years

(Cl. D3—26)

To all whom it may concern:

Be it known that I, Davis Cohen, a citizen of the United States of America, residing in Brooklyn, county of Kings, and State of New York, have invented a new, original, and ornamental Design for a Skirt or Similar Article, of which the following is a specification, reference being had to the accompanying drawing, forming part thereof,

Fig. 1 is a front view of a skirt or similar article showing my new design.

Fig. 2 is a rear view thereof.

I claim:

The ornamental design for a skirt or similar article, substantially as shown.

DAVIS COHEN.
